UNITED STATES PATENT OFFICE.

HERMAN HILENBURG, OF PHILADELPHIA, PENNSYLVANIA, ASSIGNOR TO DAVID WOLFE BRUCE, OF NEW YORK, N. Y.

DESIGN FOR A FONT OF PRINTING-TYPE.

SPECIFICATION forming part of Design No. 12,635, dated December 27, 1881.

Application filed November 17, 1881. Term of patent 14 years.

To all whom it may concern:

Be it known that I, HERMAN HILENBURG, (assignor to DAVID WOLFE BRUCE,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an ornamental letter shaded on the right and below by the heavy lines succeeded by a light line. The faces of the letters are ornamented by the rhomboidal ornaments with an open rhomboid in the center, above and below which are placed a series of heavy dots gradually diminishing in size.

The character of the design is preserved in the punctuation-marks, the rhomboidal ornament being found in the period and the heavy dots, gradually diminishing in size in the exclamation and interrogation marks and in the numerals and in the dollar and pound symbols.

In connection with this font, and forming a part of it, are the ornamented adjuncts shown after the symbols. One consists of a circular figure with heavy center, from which extend the light stamens, shaded as shown, surrounded by an outer circle. Above is placed, about centrally, a heavy lance-like figure surmounted by a heavy dot, upon each side of which are the curved lines with dot terminations. Below the outer circle the reverse of this figure is placed. The other figure consists of an upper curved figure curved to the right and having a heavy dot termination, ornamented above by a short curved line with dot termination, and a like curved figure extending downward from the upper curved figure and ornamented below by a short curved line with dot terminations. Upon the left the terminations of these curved figures are extended to form an open arched figure, from which extend to the right the four stamens shaded by the heavy lines; to the right of these a curved line, beyond which are placed the heavy dots upon each side of the curved lines with dot terminations, between which is placed a light line extending to the right and gradually widened to form a lance-like figure followed by a heavy dot.

What I claim as new is—

The design for a font of printing-type, substantially as shown and described.

HERMAN HILENBURG.
